UNITED STATES PATENT OFFICE

GEORGE L. MOORE, OF CHICAGO, ILLINOIS, ASSIGNOR TO ALEMITE CORPORATION, OF CHICAGO, ILLINOIS, A CORPORATION OF DELAWARE

MEASURING UNIT FOR LUBRICATING SYSTEMS

Application filed October 22, 1925. Serial No. 64,272.

The present invention relates to that type of lubricating system in which a lubricant is forced from a central point to a plurality of distributed discharge points; and the object of the present invention is to produce a simple and efficient measuring unit or device adapted, when placed at one of such discharge points, to segregate a predetermined quantity of the lubricating material, during each cycle of operations, and positively discharge it into a bearing to be lubricated, regardless of the pressure at the central distributing point, or the speed of operation or the length of time that the pressure is applied.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a central longitudinal section through one of my improved devices, mounted on a support containing a bearing to be lubricated, the parts being in their normal positions corresponding to lack of pressure in the system; Fig. 2 is a view similar to Fig. 1, showing the condition of the parts, after the first application of pressure after installation of the device; and Fig. 3 is a view similar to Figs. 1 and 2 showing the condition of the parts immediately after the release of pressure.

Referring to the drawing, 1 represents a small hollow cylinder closed at the bottom and having at the middle of the bottom a downwardly projecting nipple 2 to be screwed into a support. The top of the cylinder is closed by a detachable cap 3 having a central inlet port 4 to receive lubricating material from a conduit 5 leading to a central distributing point, not shown. Fitting within the cylinder and slidably lengthwise thereof is a short sleeve 6 resting on a coiled spring 7. The coiled spring in turn rests on a flat ring 8 resting on the bottom of the cylinder and surrounding the outlet passage 9 in the nipple. A spring finger 10 extends upwardly and laterally from one side of the ring 8 and

is provided at its upper end with a hook 11 that normally lies in the vicinity of the longitudinal axis of the cylinder.

The upper edge of the sleeve 6 is ground to form a seat 12 in the form of a segment of a sphere. Resting on this seat is a valve 13 having its under face curved to conform to the same spherical surface as the valve seat. The member 10 has an upwardly projecting stem provided with a conical valve 14 at the upper end, the part 14 being adapted, when the pressure in the system is relieved, to close the inlet port or passage 4. The under side of the top of the cap 3 is shaped to enclose a conical chamber 15 merging at the apex into the inlet passage 4; the walls of this chamber serving to guide the valve 14 to its seat. On the under side of the valve 13 is a downwardly projecting stem 16 having at the lower end a head 17 in the form of an inverted cone.

Normally the parts are in the position shown in Fig. 1. When pressure is applied at the central distributing station, the lubricant L in the conduit presses the valve 14 down against the resistance of the spring 7, so that lubricant enters the upper end of the cylinder. The spherical valve 13 prevents the lubricant from passing down through the interior of the sleeve 6 and therefore the sleeve is pressed down, along with the valve 13. The parts are so proportioned that as the sleeve approaches the lower limit of its movement, the conical head 17 on the valve 13 passes the hook 11 and presses the same laterally. A further downward movement of the sleeve and valve brings the parts in a position that permits the hook 11 to snap over the upwardly directed face on the conical head 17, as shown in Fig. 2. Then, when the pressure at the central distributing point is relieved and a condition is established such that the lubricant may move backwards through the conduit, the spring forces the sleeve up. However, the spherical valve is anchored, the hook tending to hold it down. It will be seen that the downward pull of the hook is applied at a point displaced laterally from the vertical axis of the valve and therefore the first result of a slight up-

ward movement of the sleeve is to tilt the valve as shown in Fig. 3; this tilting being made possible by the spherical shape of the seat and valve, the valve sliding bodily in a downward direction on one side, and the upper side rising. The lubricant in the upper part of the cylinder can now flow past the valve into the interior of the sleeve. As the sleeve continues to rise, the tilting of the valve will reach a point at which the hook will slide off the top of the head with which it engages, leaving the valve free. However, since the lubricant is now rushing down through the passage open for it, the valve will remain tilted until it approaches the inlet port, whereupon the conical walls leading to the inlet port will engage with the conical valve member 14 and straighten the valve device into the position shown in Fig. 1. The inlet passage 4 is very small in cross sectional area compared to the cross sectional area of the chamber within the cylinder 1. Consequently, when the pressure at the central distributing station is relieved, so that the spring may force the sleeve and its valve up, a back pressure is set up at the inlet passage, which now forms an outlet passage; the result being that there will be a sufficient pressure within the upper portion of the cylinder to insure that the oil that is rushing down past the valve will hold the valve open. In other words, the operation of the device does not depend upon the distance at which it is located below the distributing station, or the remoteness from such station. Therefore a plurality of such devices located at different distances from the distributing station, and at different elevations, will all operate efficiently.

If the lubricant that has been transferred from the upper part of the cylinder to the lower part does not flow freely into the bearing to be lubricated, the next cycle of operations will cause this segregated quantity of lubricating material to be forced positively out of the discharge outlet under the full pressure of the system.

It will be seen that after the valve and the sleeve have been forced down, it makes no difference how great the pressure is or how long the application of pressure may continue, since no lubricant can pass the main valve until such a time when the pressure is released and the sleeve and valve begin to move up.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A metering device for a centralized lu-

bricating system, comprising a chamber having an inlet at the top and an outlet at the bottom, said inlet adapted for connection to a conduit forming part of said system, a member, having an opening therethrough, fitting slidably into said chamber for up and down movements, means maintaining said opening closed while said member is moving downwardly, additional means for uncovering said opening when said member starts on its upward movement, and separate means tending constantly to raise said member.

2. A device of the character described, comprising a chamber having an inlet at the top and an outlet at the bottom, a member having a sliding fit in said chamber and adapted to move up and down therein, a spring tending constantly to raise said member, said member having therein an opening terminating in a concave upwardly-facing valve seat at the top, a convex valve resting on said seat, a shoulder on the under side of the valve on one side of the longitudinal axis of the valve, and a stationary spring catch in position yieldingly to engage said shoulder when the said member is in its lowermost position and afterwards cause the valve to tip and uncover said opening when said member begins to rise.

3. In a centralized lubricating system, a conduit, a metering device having an inlet and an outlet, said inlet connected to said conduit and said outlet connected to a part to be lubricated, a measuring chamber in said device, said chamber having an outlet, a laterally displaceable member normally closing the outlet of said chamber, and means for shifting said member to place said chamber and first mentioned outlet in communication.

4. A metering device for a centralized lubricating system comprising, in combination, a chamber having an inlet at the top adapted for connection to a conduit forming part of said system, a movable sleeve in said chamber having an opening therein forming an outlet for said chamber, resilient means for urging said sleeve upwardly, a displaceable member normally closing said outlet, and means engageable with said member for displacing the member relative to said sleeve to open said outlet upon movement of said sleeve in one direction.

5. A device of the character described comprising a chamber having an inlet at the top and an outlet at the bottom, a member fitting slidably in said chamber so as to be movable up and down therein, said member having an opening therethrough, a downwardly seating valve for said opening, means adapted detachably to engage with said valve when said member approaches the lower limit of its movement and to unseat the valve when the said member begins to rise and thereupon

to disengage itself, and a spring tending constantly to raise said member.

6. A metering device for a centralized lubricating system comprising a cylinder having an inlet at the top and an outlet at the bottom, a member fitting slidably in said cylinder and having an opening therethrough, a downwardly seating valve resting on said member and adapted to close said opening, a spring tending constantly to move said member upwardly, means for unseating said valve when said member moves upwardly from its lowermost position, and means for closing the valve when said member reaches the upper limit of its movement.

15 7. A metering device for a centralized lubricating system comprising a measuring chamber having a movable wall, an inlet for said chamber adapted for connection to a conduit forming a part of said system, an outlet for said chamber located in said movable wall, a spring urging said movable wall upwardly, a laterally displaceable member normally closing said outlet, and means operable upon the upward movement of said wall for displacing said member to open the outlet.

20 In testimony whereof, I sign this specification.
